ABSTRACT

A housing with an elongated stem portion has a crank-shaft mounted within the housing. A tool such as a saw or wood chipper extends through the elongated stem and is coupled to the shaft. An electric motor rotates the shaft causing reciprocal motion of the tool. A grinding wheel and a drill chuck are mounted on the shaft.

POWERED HAND TOOL

This invention relates to a powered hand tool for chipping wood, sawing, grinding and drilling. There is presently a need for a simplified design of a tool which is capable of either chiseling wood or sawing in the hand-type tool version. The tool, also, should have the capability of drilling and grinding.

We have invented an apparatus of relatively simple design capable of chiseling or sawing with grinding and drilling capabilities.

We provide a powered hand tool comprising a housing having an elongated stem portion, a crankshaft mounted within the housing, a tool within the stem portion and extending from the stem portion, means coupling the tool to the shaft in such a manner that rotation of the shaft causes reciprocating motion of the tool and means rotating the shaft and mounted within the housing.

Other objects, features and advantages of the invention will be apparent from the following description of the present preferred embodiment.

In the accompanying drawings we have shown a present preferred embodiment of the invention and have illustrated a method of practicing it in which:

FIG. 1 is a vertical sectional view of a powered hand tool;

FIG. 2 is an end view partly in section taken on the line II-II of FIG. 1;

FIG. 3 is an enlarged fragmentary view taken on the line III-III of FIG. 1;

FIG. 4 is an enlarged fragmentary view taken on the line IV-IV of FIG. 1;

FIG. 5 is an end elevational view of the retractable shield as viewed on the line V-V of FIG. 1;

FIG. 6 is a transverse sectional view of the handle and tool carrier and taken on the line VI-VI of FIG. 1;

FIG. 7 is an end elevational view from the right of FIG. 1 of a tiltable base used with alternate tooling;

FIG. 8 is a view in section of the lower handle illustrating an alternate tool adapter.

The powered hand tool comprises a housing 10 which acts as a case. The housing 10 has a first end portion 11 and a second end portion 13. A motor 12 is inserted in the first end portion 11 and drives a crankshaft 18 (18a, 18b and 18c) which extends from the first end portion 11 to the second end portion 13 of the housing 10. The crankshaft 18 is formed by a crank throw 18a, a first journal end portion 18c and a second journal end portion 18b. Drive pinion 14 coupled to motor 12 drives gear 16 keyed at 17 to the first journal end portion 18c. The crankshaft 18 is held by bearings 30, with spacers 32. An abrasive wheel (grinding wheel) 36 is journaled on the second journal end 18b of the crankshaft 18 and spaced from bearing 30 by spacer 34. One end 19 of the second journal end 18b of the crankshaft 18 is threaded to which drill chuck 40

is mounted and spaced from grinding wheel 36 by spacer 38. A retractable shield 54 covers the grinding wheel 36 when not in use.

A connecting link 20 is coupled to the crank throw 18a. A wrist pin 22 couples a reciprocating tool carrier 24 to the connecting link 20. At the top of chisel 46 is mounted a chisel shank hex head 48 which rests in the hex cavity 26. A set screw 50 locks the hex head 48 with the tool carrier 24. The tool carrier 24 and tool (chisel 46) are inserted within an elongated stem portion 28 which acts as a combination handle and guide for the tool carrier 24.

The depth of penetration of the tool whether a chisel 46 or saw blade 60 is adjustable by adjustable depth gauge 42 provided with a tiltable shoe 44.

The chisel 46 can be replaced by the saw adapter 58 with blade 60 and tiltable shoe 62. This is done by removal of set screw 50 and replacement of the saw adapter 58 which fits into the hex cavity 26 of the tool carrier 24.

A handle 52 on housing 10 enables holding the tool as well as elongated stem 28.

A plate 56 enables the electric motor 12 to be inserted and removed.

The operation of the powered hand tool is as follows: the motor turns the crankshaft causing reciprocating motion of the tool carrier member 24 which carries either the chisel 46 or the saw 60. The grinding wheel 36 acts as a "fly wheel" to provide an even torque during initial drilling, wood chipping or sawing.

We claim:

1. A powered hand tool comprising:
1. a housing comprising a main tubular portion and a second tubular portion intersecting said main portion at a right angle between the ends thereof;
2. a crankshaft within the main portion of said housing having a crank in registry with said second portion of said housing;
3. bearing means on opposite sides of said crank supporting said crankshaft within the main portion of said housing;
4. a tool reciprocatively mounted within said second portion of the housing and operated by said crank;
5. motor means at one end of said main portion of the housing drivingly connected to said crankshaft;
6. a grinding wheel within the main portion of the housing adjacent the end opposite said motor means;
7. and a drill chuck mounted on the end of said crankshaft opposite said motor means.

2. A powered hand tool according to claim 1, wherein the main portion of said housing includes a handle, said handle being diametrically opposite said second tubular portion of the housing and enabling the operator to hold the tool for operation of the drill chuck, the tool or the grinding wheel.
